UNITED STATES PATENT OFFICE.

EDWARD F. DUDLEY, OF OAK PARK, ILLINOIS, ASSIGNOR TO MIEHLE PRINTING PRESS & MANUFACTURING COMPANY, OF CHICAGO, ILLINOIS, A CORPORATION OF ILLINOIS.

BED-MOTION.

1,367,466.

Specification of Letters Patent.

Patented Feb. 1, 1921.

Original application filed September 2, 1916, Serial No. 118,189. Divided and application filed January 31, 1918, Serial No. 214,616. Divided and this application filed September 16, 1919. Serial No. 324,126.

To all whom it may concern:

Be it known that I, EDWARD F. DUDLEY, a citizen of the United States, residing at Oak Park, in the county of Cook and State of Illinois, have invented certain new and useful Improvements in Bed-Motions, of which the following is a specification, the same being a division of my co-pending application Serial No. 214,616, filed January 31, 1918, and which, in turn, is a division of my application Serial No. 118,189, filed September 2, 1916, patented November 5, 1918, as No. 1,284,183.

The invention relates to mechanism for converting rotary motion into to and fro rectilinear or reciprocating motion. It has more especial reference to means of this kind for utilizing rotary motion for reciprocating the bed of a printing press or like machine.

In devices for this purpose the bed is driven throughout the greater part of its stroke at a constant rate of speed by suitable constant speed mechanism, and is slowed down, stopped, and started on its return stroke at each end of its travel by reversing mechanism embodying devices giving the bed a rate of speed gradually decreasing from the maximum speed to a point of rest and increasing from such point of rest until the maximum speed is again attained.

It has been usual in mechanism of this character to employ such shifting devices comprising parts which reciprocate with the bed and at the time of reversal are moving in the same direction as the bed, thus disadvantageously adding their momentum to that of the bed, the total of which must be overcome to bring the latter to a stop for reversal. It has also been customary to employ gears axially shifted to bring them into engagement alternately with oppositely rotating gears in order to reverse the direction of bed travel. Likewise, an objectionable feature found in bed shifting mechanism is the disposition of the operating parts at such distance below the plane of the bed as to preclude the employment of sufficiently massive and most efficiently distributed supporting pillars.

By the invention of my Patent 1,284,183 (a partial description of the construction of which is embodied herein for purposes of a clear understanding of my present inven-

tion) the bed reversing devices reciprocate, at the moment of reversal, in a direction counter to the direction of movement of the bed prior to reversal, thus aiding in neutralizing the jars and strains incident to reversal and due to the momentum of the bed and counteracting the tendency of the press to slide on the floor, thus minimizing the strains on the press frame. These bed shifting devices are, moreover, on the same side of the center of gravity of the press as the bed itself thus avoiding any torsional strain on the press in a vertical plane tending to tip the press upon reversal. Furthermore, by the construction of my co-pending application Serial No. 214,616, as also by the present invention which is a modification and division thereof, shiftable gears are dispensed with and the power is transmitted by the gears in a constant manner without shock.

Other advantageous characteristics of the invention from the standpoint of simplicity, compactness, efficiency and dependability for the purposes intended will be apparent to those skilled in the art from a further consideration of the constructional features of the present invention as set forth, by way of example, in the following detailed description of an embodiment thereof as illustrated in the accompanying drawings, wherein:

Figure 1 is a view illustrating in side elevation a printing press embodying the invention;

Fig. 2 is a partial transverse vertical section on the line 2—2 of Fig. 1;

Fig. 3 is a central transverse vertical section taken on the line 3—3 of Fig. 1;

Fig. 4 is a side elevation of Fig. 3; and

Fig. 5 is a section on the line 5—5 of Fig. 3.

In the drawings, the frame of the press is indicated generally at 11, the printing cylinder at 12 suitably journaled in the frame, details not shown, and the central supporting pillar at 13. These old and well known elements of press construction are shown in a diagrammatic manner only, being of any well known type and arrangement.

Power from any suitable source is transmitted by the power shaft 14, the gear 15, the gear 16 and the gear 17 for rotating the

- impression cylinder 12 at a constant speed in a given direction. The shaft 18 of the gear 16 carries in addition to the gear 16 a gear 19 and a crank arm 20.
- 5 Power is also transmitted from the shaft 18 through the gear 19 to a gear 21 mounted upon the sub-shaft 22 and having teeth 23 which may be of uniform width. Formed integral with the gear 21 or bolted thereto as 10 indicated in fixed relation are two segment gears 24 and 25, the former lying immediately adjacent the gear 21 and the latter separated therefrom by the width of the segment gear 24. The segment gear 24 extends 15 through an arc of 120 degrees, as does also the segment gear 25, the two segments being angularly displaced so that the gap on one side of the shaft 22 embraces an arc of $30\frac{1}{2}$ degrees, while the gap on the other side 20 embraces an arc of $89\frac{1}{2}$ degrees.
- A countershaft 26 is mounted in the machine frame parallel to the shaft 18 and carries a pinion 27 which is constantly in mesh with a rack 28 downwardly facing from the 25 bed 29.
- Upon the countershaft 26 which carries the pinion 27 is mounted a pair of pinions 30 and 31, the former arranged to mesh with the segment gear 24. Alongside the counter-shaft 26 is a stub shaft 32 carrying a wide or double faced pinion 33, one-half of the face of which is arranged to mesh with the segment gear 25 while the other half thereof is in mesh constantly with the pinion 31.
- 30 The wide gear 33 runs idly upon the stub shaft 32 and serves for the reversal of the direction of rotation of the shaft 26 during the time the said pinion 33 is driven by the segment gear 25.
- 35 The operation of this gear train is as follows: The gear 21 and the segment gears 24 and 25 being constantly driven in the direction indicated by the arrows in Figs. 4 and 5, the segment gear 24 comes into mesh with 40 the pinion 30 a sufficient length of time after the segment gear 25 has left the pinion 33 to permit of the reversal of the bed as previously described, by the reversing mechanism. The pinion 30 is driven by the segment gear 24 in a counter-clockwise direction thus moving the bed to the left through the mediation of the shaft 26 and pinion 27 meshing with the rack 28. After the teeth of the segment gear 24 clear those of the pinion 30, and allowing the same interval for the reversing of the direction of bed movement by the reversing mechanism, the teeth of the segment gear 25 come into mesh with the teeth of the pinion 33 rotating this 45 pinion in a counter-clockwise direction and the movement of the pinion 33 being transmitted through the pinion 31 to the shaft 26, causing the latter to move in a clockwise direction and through the mediation of the pinion 27 and the rack 28 moving the bed to 50 the right. During the functioning of the segment gear 25 the pinion 33 is thus used for driving the bed in a reverse direction, but during the functioning of the segment gear 24 the pinion 33 is running idle. It will 55 be readily understood that the difference in the gap of $30\frac{1}{2}$ degrees and the gap of $89\frac{1}{2}$ degrees on the two sides of the shaft 22 is to compensate for the disposition of the pinions 30 and 31 on the one hand and the pinion 33 on the other in advance of each other, there being a net interval of 60 degrees of arc between the segment gears 24 and 25 to allow for the functioning of the reversing mechanism to slow down, stop and accelerate the speed of the bed in the opposite direction, as will now be described.
- The crank arm 20 previously referred to as being fixed upon the end of the shaft 18 is connected by means of a wrist pin 34 to a link 35, the opposite end of which is pivoted at 36 to a reversing bar 37 guided within bracket guides 38, 39 for rectilinear reciprocating motion above the shaft 14 and slightly below the plane of the bed 29. This reversing bar 37 is provided near its ends on the upper face with racks 40, 41 in mesh respectively with loose pinions 42, 43 on stationary shafts 44 and 45 or, obviously, the pinions may be tight thereon and the shafts suitably journaled in the frame. The shafts 44, 45 have also mounted thereon pinions 46 and 47, the teeth of which extend into the horizontal plane of the rack 28 but to one side thereof. Intermediate the two ends 45 of the bed 29 alongside the rack 28, in the vertical plane of the pinions 46, 47 is a non-continuous or interrupted rack 48, 49, the rack portions of which are adapted to be engaged by the pinions 46, 47 immediately before, at the time of, and after the reversal of the direction of bed movement, the pinions 46 and 47 taking control of the bed through the means of the short rack portions 48 and 49 immediately before the gears 30 and 33 leave the segments 24 and 25, during the interval of time when neither the gears 30 or 33 is in mesh with either of the segments 24 or 25, and for a slight length of time after the gears 30 and 33 again engage the respective segments. The bed motion is thus during the period of reversal under the control of the reciprocating bar 37, such control being received from the segments 24 and 25 of the regular bed drive at the exact speed 50 of the bed movement between reversal points, without shock, the speed of the bed during the time it is controlled by the reversing bar 37 decreasing gradually from the full normal speed thereof to a standstill at the point of reversal and then gradually increasing until the speed of the bed drive is attained.
- A noteworthy feature of the reversing mechanism is the fact that as the bed is slowing up under the control of the reversing 55

bar, the said reversing bar is moving in a direction opposite to that of the bed, the momentum of the latter serving to neutralize the jars of reversing and to counteract the effect on the press frame of the momentum of the bed as the latter is being slowed down, in contradistinction to the usual form of device in which the reversing mechanism is moving at the time of reversal in the same direction as the bed, whereby the tendency to skid the press on the floor and the consequent strain on the frame is augmented. At the instant of reversal, the bed being stationary, the reciprocating reversing bar 37 is also stationary, the crank arm 20 being at dead center. All the advantages of the arcual motion of the crank are thus utilized, the increase in motion of the reversing bar 37 being gradual from the dead center of the crank as it travels through an arc of 90 degrees, at which time the bed is moving at its maximum speed and is then transferred to the regular drive. It will also be observed that by employment of the angularly disposed segment gears 24, 25, coöperating with the pinions 30 and 31 and the idler pinion 33, the bed is driven alternately in opposite directions from the same drive shaft without the employment of gears shiftable upon their axes into and out of engagement with other gears. Moreover by the arrangement herein set forth, all of the bed reversing mechanism is confined vertically to a space immediately below the bed whereby the lower space is utilizable for heavy pillars and other massive supports for the press, thus lending greater stability. It is to be noted that if the reversing bar 37 were disposed below the center of gravity of the press, the movement of the reversing bar at the time of reversal counter to the direction of movement of the bed would by its momentum augment the momentum of the bed in the way of a tendency to upend the press or subject the same to a torsional strain in a vertical plane about the center of gravity. The arrangement of the reversing bar immediately below the bed and its movement counter to that of the bed at the time of reversal assists in neutralizing the strains during the reversing without a tendency to upend the press and with a less strain upon the frame than would otherwise be the case. It also should be observed that by means of the gear train forming the subject matter of the present application, the driving, stopping and reversing of the bed motion is accomplished without the employment of axially shifted gears, by the employment of segment gears driven in the same direction as distinguished from segment gears driven in opposite directions as set forth in application Serial No. 214,616 of which this case is a division.

I claim:

1. The combination with a reciprocable bed, of a gear train for driving it alternately in opposite directions through the medial portion of its travel, the gear train including angularly displaced toothed sectors disposed in adjacent parallel planes, said sectors rotating in the same direction and one acting directly and the other through the medium of an idler. 75

2. The combination with a reciprocable bed, of a gear train acting by a single rack attached to the bed to drive it alternately in opposite directions through the medial portion of its travel, said train including 80 angularly displaced toothed sectors having fixed relation to each other disposed in adjacent parallel planes, one acting directly and the other through the medium of an idler. 85

3. The combination with a reciprocable bed, of a gear train operating by a single rack attached to the bed to drive it alternately in opposite directions through the medial portion of its travel, a separate gear 90 train operating to slow down, reverse and accelerate the bed when it is delivered to it by the first gearing near each end of the stroke, the first gear train including angularly displaced toothed sectors disposed in 95 adjacent parallel planes, one acting directly and the other through the medium of an idler, the angular extent of the segments and the relative angular displacement thereof being such as to leave a substantial gap 100 therebetween at each end to enable the control of the bed to be taken over by the reversing mechanism.

4. The combination with a reciprocable bed, of a gear train operating by a single 105 rack attached to the bed to drive it alternately in opposite directions through the medial portion of its travel, a separate gear train operating to slow down, reverse and accelerate the bed when it is delivered to 110 it by the first train of gearing near each end of the stroke, the first gear train consisting of members fixed against axial shifting and including segment gears rotating in the same direction and acting in succession, one directly and the other through the medium of an idler. 115

5. The combination with a reciprocable bed, of means for driving the same alternately in opposite directions and comprising a countershaft having two pinions thereon, a continuously-rotating drive shaft, two trains of gearing for alternately connecting the drive and countershaft and each train including a gear having a minor segment of teeth, the teeth of one segment arranged to mesh with one of the pinions on the countershaft, and an idler gear interposed between the other segment gear and the other pinion on the countershaft where- 125 130

4
by to drive the countershaft alternately in opposite directions.

6. The combination with a reciprocable bed, of means for driving the same alternately in opposite directions and comprising a countershaft having two pinions thereon, a continuously rotating drive shaft, two trains of gearing for alternately connecting the drive and countershaft and each 10 train including a gear having a minor segment of teeth, the toothed segments of the two gears angularly displaced and together occupying less than 360 degrees with gaps at each end, one segment arranged to mesh 15 with one of the pinions on the countershaft, and an idler gear interposed between the other segment gear and the other pinion on the countershaft whereby to drive the countershaft alternately in opposite directions.
7. The combination with a reciprocable bed, of means for driving the same alternately in opposite directions and comprising a countershaft having two pinions 20 thereon, a continuously rotating drive shaft, two trains of gearing for alternately con-

necting the drive and countershaft and each train including a gear having a minor segment of teeth, the toothed segments of the two gears angularly displaced and the angular extent of each being such as to leave a substantial gap therebetween at each end whereby to relinquish the control of the bed near the limit of its travel in each direction, the teeth of one segment arranged to mesh 30 with one of the pinions on the countershaft, and an idler gear interposed between the other segment gear and the other pinion on the countershaft, whereby to drive the countershaft in opposite directions alternately after each relinquishment of control, and a separate gear train operating to slow down, reverse and accelerate the bed when delivered to it by the first train of gears 35 near each end of the stroke.

In testimony whereof I have hereunto signed my name in the presence of two subscribing witnesses.

EDWARD F. DUDLEY.
